Atty.

This is a continuation-in-part of my application, Serial No. 166,323, filed June 6, 1950, for "Latching Means for Staple Supporting Slides," which application is now pending.

UNITED STATES PATENT OFFICE

2,599,131

LATCHING MEANS FOR STAPLE SUPPORTING SLIDES

George J. Rundblad, Elmwood Park, Ill., assignor to Wilson-Jones Company, Chicago, Ill., a corporation of Massachusetts

Application June 6, 1950, Serial No. 166,323

5 Claims. (Cl. 1—3)

1

This invention relates to latching means for staple supporting slides in stapling machines, and has particular reference to a flexible compensator for the latch which secures the staple slide in position in the stapling machine.

It is a primary object of the present invention to provide a simple and inexpensive flexible compensator that will impart sufficient flexibility of adjustment to the latch to permit a secure fit without excessive wear on the ears of the latch or the base casting adjacent the recesses in which the ears fit. The flexible compensator is particularly designed for use with a staple slide of the type disclosed in the application of Herbert W. Marano filed July 7, 1949, under Serial No. 103,420, but may be used with any similar slide. With slides of this type it has been found that either because of the hinge curl on the latch, or because of irregularities in the castings from which the base of the stapling machine is made, the ears of the latch do not always fit properly into the recesses of the base portion. The result is that the ears of the latch are forced into position and are either distorted or the recess is nicked. If the ears of the latch are distorted it is difficult to secure the latch in position, and if the casting becomes worn the latch may not hold the slide securely.

Other objects of the invention will become apparent upon reading the following description, taken in conjunction with the accompanying drawing, in which:

Figure 1 is a perspective view of a stapling machine in which the invention is embodied, with the body portion swung around its pivot to show the latch and flexible compensator relative to the stapling machine;

Figure 2 is an enlarged fragmentary perspective view of the rear portion of the stapling machine body showing the flexible compensator in position relative to the staple slide;

Figure 3 is a detail perspective view showing the flexible compensator and the rear portion of the staple slide in disassembled position;

Figure 4 is a fragmentary longitudinal sectional view showing the flexible compensator and the latch associated with the staple slide;

Figure 5 is a cross sectional view, taken along the line 5—5 of Figure 4; and

Figure 6 is a fragmentary top elevational view of the rear portion of the staple slide showing the flexible compensator and latch in assembled position.

Referring to the drawing, the stapling machine comprises a base portion 2 and a body portion 3

hinged thereto, as indicated at 4. A staple slide 5 is mounted in the body portion in any suitable manner. The top wall 6 of the staple slide is provided with a loop 7 which is preferably struck out therefrom, but may be formed as a separate strap and welded or riveted thereto.

The flexible compensator, which replaces the conventional rear end wall of the staple slide, comprises a resilient strip bent at right angles to form a rear wall 8 and a flat top 9. The flat top 9 is provided with a forwardly extending tongue 10 adapted to be inserted between the loop or strap 7 and the top wall of the staple slide. The tongue 10 has a restricted portion 11 and the loop 7 is indented, as indicated at 12, after the tongue has been inserted between it and the top wall 6, to hold the flexible compensator securely in place. The wall 8 is provided with an aperture 13 to receive the guide rod 14 of the staple slide, and a slot 15 to receive the curl 16 of a latch 17 to pivotally secure the latch to the flexible compensator.

The lower edge of body portion 3 is provided with a pair of recesses 18 designed to receive the ears 19 of the latch to hold the staple slide in the body portion of the stapling machine. If the hinge curl 16 is too tight or too loose, or if the ears 19 do not fit properly into the recesses 18 for any other reason, the resilience of the flexible compensator permits flexing of the wall 8 to an extent sufficient to make the ears 19 engage the recesses 18 with the proper friction so that the slide is held in place. This resilience also facilitates the disengagement of the ears 19 from the recesses whenever it is necessary to remove the staple slide for any purpose.

Although I have described a preferred embodiment of my invention in considerable detail, it will be understood that the description there-of is intended to be illustrative, rather than restrictive, as many details may be modified or changed without departing from the invention. Accordingly, I do not desire to be restricted to the exact structure described, except as limited by the appended claims.

I claim:

1. In a stapling machine, a body portion, a staple slide, a flexible compensator secured adjacent the rear end of said staple slide, and a latch pivotally secured to said flexible compensator, said latch being engageable with said body portion to secure said staple slide on said body portion.

2. In a stapling machine, a staple slide, a latch for holding said staple slide in predeter-

mined position in said stapling machine, and a resilient member secured to one end of said staple slide, said latch being pivotally secured to said resilient member.

3. In a stapling machine, a body portion provided with a pair of recesses, a staple slide positioned in said body portion, a flexible compensator secured adjacent one end of said staple slide, a latch secured to said compensator, said latch being engageable with said recesses to hold said staple slide in said stapling machine.

4. In a stapling machine, a body portion provided with a pair of recesses, a staple slide positioned in said body portion, a spring compensator having a tongue rigidly secured to one end of said staple slide and a rear wall positioned adjacent said end of the staple slide, and a latch secured to said rear wall, said latch having a pair of ears engageable with said recesses to hold said staple slide in said body portion.

5. In a stapling machine, a body portion having a pair of recesses in its lower edge, a staple

slide positioned in said body portion, said staple slide having a loop projecting below its top wall, a flexible compensator comprising a flat top and a rear wall substantially perpendicular to said top, said top being rigidly secured between said loop and the top wall of said staple slide, a latch pivotally secured to said rear wall, and a pair of ears on opposite edges of said latch, said ears engaging said recesses to hold said staple slide in said body portion of the stapling machine.

GEORGE J. RUNDBLAD.
